CIRCULAR KNITTING MACHINE

J. Stanley Preston, Bronxville, N. Y., assignor to
Jacquard Knitting Machine Co., Inc., Philadelphia, Pa., a corporation of New York

Application October 14, 1938, Serial No. 234,882

11 Claims. (Cl. 66—50)

My invention relates to circular knitting machines in which the needle bank or banks rotate.

Heretofore various forms of mechanisms operating under the direction of patterns of paper or other thin sheet-like materials, have been devised to control the operations of each stitch-forming element of a circular bank in knitting machines of the kind in which the needle bank or banks (and the bank of controlled stitch-forming elements) is stationary. As a result it has been possible to knit fabrics having complex structures, designs and fancy effects, and structures and designs of large repeats, worked out with various kinds of stitching, on machines of the stationary needle bed type. Heretofore however it has not been possible to knit such complex fabrics on knitting machines of the rotary needle bed type, at least with great facility. Generally speaking, my invention provides for the knitting of the same complex structures on the latter type of machine and in an efficient manner; it applies, as it were, the principles of the pattern mechanisms of the complex-fabric-stationary-needle-bank knitting machines to the control of the operations of stitch-forming elements assembled in rotating banks, or the control of the operations of so many of such stitch-forming elements, and at such and as many feeds, as may be necessary or deemed desirable in any instance. Instead of controlling the operations of strictly individual stitch-forming elements however, the operations of individual sets of small numbers of adjacent stitch-forming elements may be controlled by my invention, as will be understood from the practices with stationary bed machines.

As will be apparent accordingly, my invention is applicable to machines in which the bank of controlled stitch-forming elements has the form of a cylinder or the form of a flat annulus or dial, and to machines having both dial and cylinder banks. It will also be apparent from the practices with knitting machines, and especially from the practices with stationary bed machines, that my invention is applicable to, and that within the term stitch-forming elements I refer to, needles, sinkers, pressers, wale-thread feeders, stitch-transferring members, and in general all kinds of knitting machine instruments arranged in banks of a considerable number of instruments per bank and the control of which will control the production of substantially individual stitches and thus result in the production of pattern or fancy work and variations in the knitted structure.

The general nature of my invention can best be pointed out after I have described the machine

illustrated in the accompanying drawings, which show an eight-feed rotary cylinder machine wherein sliding latch needles are caused to take or omit taking yarn as and where desired under the control of a pattern of paper or the like, so that (yarns of various colors being supplied at different feeds) a fabric can be knitted in part of one color and in part of another color or colors as the desired design may call for. In those drawings:

Fig. 1 is a plan view of the machine, substantially all of the associated and accessory parts ordinarily employed with such machines being omitted from the drawing for clarity of illustration; however, that is to say, substantially only those parts directly concerned with my invention being shown; Fig. 2 is a sectional view on the line II—II of Fig. 1; Fig. 3 is an elevation, partly in section, of one of the pattern sections of Fig. 1 and substantially on the line III—III of Fig. 6; Fig. 4 is a sectional plan view substantially on the line IV—IV of Fig. 3; Fig. 5 is an end view, looking outwardly from the cylinder, illustrating particularly the arrangement of the couplers of each pattern section; Fig. 6 is a sectional view substantially on the line VI—VI of Fig. 3; Fig. 7 is a plan view of a portion of the cam plate connected to the needle cylinder, part of the cylinder being shown in section; and Fig. 8 is a diagrammatic view illustrating the relation between the cams, needles and associated mechanisms of the machine of Fig. 1.

In the machine illustrated, the needle cylinder 1 carries sliding latch needles 2 in external slots 3 as will be understood. The cylinder 1 is mounted for rotation on the stationary base 3. A stationary cam cylinder 4 encircles the needle cylinder 1 to support various of the cams for operating the needles 2 and their associated jacks; the cam cylinder 4 is mounted on a horizontal extension 5 which rests on side walls 6 of the various sections of the pattern mechanism later described, and these side walls are mounted on a cover plate 7 of the machine base as illustrated in Fig. 2. An annular extension 8 from the needle cylinder 1 is provided at its outer edge with gear teeth 9 meshing with a power-driven gear wheel 10 (Fig. 1), which rotates the needle cylinder continuously in the direction shown by the arrow 11 in Figs. 4, 7 and 8. It will be understood that these various parts, like the remainder of the mechanism illustrated, are subject to considerable modification in form and arrangement. It will be understood also that the needles 2 are representative of the class of stitch-forming elements to which

my invention relates, and that my invention is not limited either to sliding latch needles or to the control of needles, as before indicated.

Primarily for convenience of construction and operation, jacks 15 are provided, say one for each needle; each jack slides in an extension of the cylinder slot containing its respective needle. From one aspect the jacks constitute part of the needle-controlling mechanism as will be explained; from another aspect they constitute bare extensions of their respective needles. Each feed includes a stationary cam 16 to project (i. e., here raise) the needles to take the yarns into their hooks, a stationary guide 17 to lead yarn to the needles raised by its associated cam 16 as will be understood, and a stationary cam 18 for purposes later described. The yarn guides may be mounted on any convenient stationary part of the machine; the raising cams 16 and their associated cams 18 (Fig. 8) are mounted on the inner periphery of the cover plate 7 (Figs. 2 and 3). Each jack 15 is provided with a butt 19 at its lower end for engagement with the cams 18, and also for engagement with the cams 16 when permitted by the pattern or patterns; therethrough the cams 16 raise the jacks and therewith the respective needles; the butts 19 are all located the same distance from the lower ends of the various jacks. The cams 16 may raise the needles high enough to take yarn from the yarn guides 17, and even high enough to thrust the latches of the needles through the loops of yarn previously drawn by and hanging on the needles, that is to say, high enough to clear the loops below the needle latches. In the alternative, the raising cams 16 or some of them may raise the needles only high enough to place the butts of the needles 2 above a respectively associated stationary cam (say cam 20, and say one for each feed, Fig. 8) which is so placed as to raise to yarn taking position or to clearing position any needle landing on it; for example, the cams 16 may raise the needles high enough to take yarn but without clearing while the associated cams 20 raise the needles landed on them to clearing position, so that tuck stitches can be made by the cams 16 by omitting some of the cams 20 or taking some of them out of action temporarily, or knit stitches can be made by using the cams 20. Stationary stitch cams 21, one in each feed, engage the needle butts to retract the raised needles to draw new loops of the yarns and cast off the old loops, as will be understood. In acting on the needles, the stitch cams 21 may return the jacks 15 to their lowermost positions, but preferably I use cams 22, one for each feed, to act directly on butts 23 of the jacks 15 to retract the latter slightly in advance of the retraction of the respective needles; the butts 23 are located at equal distances from the lower ends of the jacks. The needle cams 20 and 21 and the jack-returning cams 22, may be mounted on the interior of the cam cylinder 4.

In order to make the needles take yarn from the various yarn guides 17 selectively as desired, I control the raising of the needles by the cams 16 by means of a pattern element or pattern elements located in, say, fixed positions; that is to say, the pattern element or pattern elements do not rotate with the bank of stitch-forming elements it or they control. To this end the slots in the needle cylinder 1 in which the jacks 15 lie are made so deep (horizontally) that when the lower ends of the jacks 15 are pushed toward the backs of the slots their butts

19 pass behind the cams 16 as the cylinder rotates, rather than over those cams (Fig. 2); obviously when any jack thus misses any raising cam 16 the respective needle remains down and accordingly does not take yarn from the yarn guide related to that cam 16. The mechanism or devices which hold the jacks 15 in their slots, for example a spring or spring 24 encircling the needle cylinder 1, may be so arranged that this mechanism permits the jacks 15 to stand in any position in their slots, forward or back, in which they may be placed; if necessary or desirable, means can be provided to assure the jacks remaining properly in their assigned positions, either by frictional engagement with their slot walls or otherwise. To return to the cam paths any butts 19 that have been placed back of a cam 16, the lower end of each jack slot is bevelled or cammed as at 25 (Figs. 2 and 3) so that as a jack-retracting cam (e. g. one of the cams 22) thrusts the jacks to the lower end of their slots, the lower ends of all backwardly-placed jacks are moved outwardly sufficiently to return their butts 19 to positions where they can engage the raising cams; sufficient space is left at 26 (Fig. 8) between each raising cam 16 and the end of the cam 18 of the following feed to permit the butts 19 of the jacks to move outwardly to the necessary extent without interference. To the rear of each space 26 as the needle cylinder rotates, a cam 28 (or inclined end of the adjacent supplemental cam 18) serves to engage underneath the butts 19 of all jacks as they leave these respective spaces and raise the jacks sufficiently to place their lower ends above the bevelled or cammed surfaces 25, but not, ordinarily, high enough to affect the operation of their needles. Thus in advance of each raising cam 16 each jack assumes a position where it can be thrust to the back of its slot so as to escape engagement with the respective raising cam; if it is left in this position it passes over the respective raising cam and raises its needle, and if it is thrust back it escapes that raising cam and leaves its needle down, but subsequently is thrust outwardly again in time to engage the raising cam 16 of the feed which follows. As may now be pointed out, the pattern or patterns and associated mechanism act to thrust jacks to the backs of their slots in the interval between a cam 28 and the raising cam 16 of the same feed, and may act thus in advance of any or all the raising cams, i. e. at each feed. The extension or supplemental cams 18 are simply to prevent the jacks 15 from moving downwardly inadvertently while in the intervals or control spaces between 28 and 16, and their actions may be supplemented by corresponding opposing cams 27 (Fig. 8) acting on the jack butts 23 to prevent the jacks creeping upwardly. The minimum length of each control space (that is to say, the distance between each initial-raising cam 28 and the needle-projecting 16 to the rear of it in each feed whereat the needle action is to be controlled), is determined by the time required to make new pattern calls, as will be understood from what follows.

In order to permit the various jacks 15 to be pushed to the backs of their slots individually, e. g. each independently of its adjacent jacks, by, say, individual devices mounted in fixed (e. g. non-rotating) position outside the cylinder, the jacks (or at least the jacks of such needles as are to be controlled), are differentiated from each other by lots of succeeding jacks; the differentiation may be by any manner that permits the

jacks to be controlled individually by devices outside the cylinder. The number of adjacent jacks (and thereby needles) in each lot may be fixed by constructional considerations, but other than this the number of differentiated jacks will be fixed, speaking generally, by the number of couplers that can be controlled readily by one pattern or pattern section, as will appear hereafter. Generally also, all controlled lots of needles and jacks will include equal numbers of differentiated jacks, although that is not entirely necessary. In the machine illustrated (Fig. 8), each lot contains thirty-six successive jacks, one lot including all the jacks from 15^a to 15^b, the adjacent lot the jacks from 15^c to 15^d, and the jack 15^e is the first of the next lot; the jacks of the whole bank of needles 2 may be composed of such lots as these, or only the jacks of such needles as are to be controlled. The jacks 15 (and thereby the needles) of each lot are differentiated in the present instance by the placement of butts 30 on the jacks at different positions with respect to the jack ends and the cylinder surface; specifically, in each lot these control butts 30 are placed at successively higher positions, i. e., successively farther from the lower ends of the jacks (Fig. 8), so that if the jacks of a lot were placed with their lower ends in a single line, their control butts 30 would lie in a single continuous diagonal line reaching, say, from near the lower righthand corner of the lot to near the upper lefthand corner of the lot. Such diagonal placement of the control butts 30 is substantially shown in the lot 15^c—15^d of Fig. 8 where none of the jacks are shown as being raised by a cam 16 at the moment; it will be observed however that certain cams acting on the lot 15^c—15^d have so displaced some of these jacks that their butts 30 do not appear in a strict diagonal. Further, each control butt 30 is placed distinctly higher than the one below it, so that a member outside the cylinder can engage any one of these butts without engaging another also. Preferably all the lots are differentiated alike; that is to say, for example, if the jacks and needles of one lot are differentiated by a left-downwardly-to-the-right diagonal placement of control butts, then preferably the needles of each and every other lot are differentiated by a similar placement of their control butts, and the control butts of the first jacks of all the lots are at equal distances from their butts 19, the control butts of the second jacks of all the lots are at equal distances from the butts 19 of those second jacks, and so on; differentiation of all the lots alike is not necessary however. It will be observed of course that pushing inwardly on the butt 30 of any jack while that jack is anywhere within one of the control spaces (i. e., is between the cam 27 and the cam extension 18 below it), the lower end of that jack can be pressed inwardly (see Fig. 2) and thereby its raising butt 19 is placed back of a raising cam 16 as and with the result before described.

Pattern mechanism, outside the cylinder, may direct the action on the control butts 30 to thus displace the raising butts 19 at each feed whereat the knitting is to be controlled; accordingly the knitting can be controlled at every needle in every feed. In the present machine a pattern mechanism or pattern mechanism section is provided for every feed to this end. As appears in Figs. 1, 3 and 4, each of the eight pattern mechanisms or pattern mechanism sections illustrated is constructed and operated in accordance with

the principles of the various pattern mechanisms employing paper patterns that have been used heretofore in stationary cylinder knitting machines. Each has a pattern drum 34 keyed to a shaft 33 mounted at its ends in the two side plates 6 of the mechanism; longitudinal slots 35 are provided in the periphery of the drum. A belt 36 of paper or the like on each drum constitutes the pattern, or more properly speaking perhaps, each of the eight constitutes a section of the pattern, considering the set of eight as a whole. These patterns 36 are perforated in accordance with the design to be knitted, each being perforated to direct the stitching of the feed to which it is related, and the pattern perforations of each being arranged in substantially transverse rows; each row is so placed that it falls on one of the slots 35 of its drum as the drum rotates to advance the pattern belt 36 on it. Side perforations in the belt entered by projections 37 on the two ends of each drum assure its belt being carried along with the drum as the drum rotates. Each drum 34 is rotated step by step at the proper times as later described; each step advances the drum the distance between the center lines of two adjacent slots 35 and hence each step of a drum produces a new call by its pattern 36. A plurality of feelers 38, to feel the pattern for its perforations, are arranged in a row above each pattern drum 34; there are as many feelers 38 for each pattern section as there are differentiations of jacks 15 (and accordingly differentiations of needles 2) in each lot 15^a—15^b, 15^c—15^d, etc., assuming that each needle or each set of a small number of adjacent needles is to be controlled individually. In the present instance, each feeler comprises a substantially horizontal bar provided with a downwardly projecting finger 39, immediately at the place where each drum slot 35 comes to rest, and each is hinged on a cross bar 40; the pattern perforations in the pattern 36 are disposed for presentation to the fingers 39, and except as the fingers may be raised momentarily, as when the pattern 36 is being advanced, each finger rests on the paper until a perforation is presented to it, and then falls through the pattern into the slot 35 below it, allowing its feeler 38 to turn on its hinge 40 as shown in Fig. 3. Elongated openings 41 in these feelers 38, through which the cross bar 40 passes, permit the feelers to be moved longitudinally also, and each feeler is provided with a butt 42 on its upper edge for engagement by a horizontally reciprocating ram 43 carried by cross heads 44 sliding in holes piercing the two side plates 6 of the pattern section. The butts 42 of all feelers whose fingers 39 rest on imperforate parts of the pattern 36, stand in the path of the ram 43; but the butts 42 are of such height that when a feeler finds a pattern perforation below its finger 39 and thus turns to its lower position, the butt 42 of that feeler then stands below the path of the ram 43 (Fig. 3). Following each call of the pattern 36 on the feelers, the reciprocation of the ram 43 carries inwardly (toward the needle bank) all those feelers 38 whose fingers have not found perforations in the pattern below them, and thereby actuate couplers in a manner to transmit the call of the pattern to the needle bank. The feelers may be returned to their outer positions again by mechanism later described. The side plates 6 of each pattern mechanism or pattern mechanism section are mounted on the base cover plate 7 as before mentioned (Figs. 2 and 3), that is to say in a fixed position.

Couplers transmit the calls of the patterns or pattern sections to the needle bank. Conveniently, these couplers are assembled in groups, and there is one group for each controlled feed, and each is directed by one of the pattern mechanisms, as in the machine illustrated. In such arrangements there may be as many couplers in each group as there are differentiated needles in each lot, and, also, the number of couplers in each group may equal the number of feelers in its pattern mechanism. Each coupler comprises a sliding member 49; its outer end is located adjacent the inner end of one of the feelers 38 (Figs. 3 and 4); its inner end 51 is inclined or cammed in such a direction (Fig. 4) that if it is struck by one of the control butts 30 of a jack 15 as the bank rotates, it will thrust that jack to the back of its slot and thus place the raising butt 19 of that jack out of the reach of a raising cam 16 as before mentioned. The cam ends 51 of each group of couplers are assembled at the control station (e. g. between cams 18, 27; see Fig. 8) of the feed it serves, and are disposed at successively higher levels and respectively at the same heights as the control butts 30 of the differentiated jacks 15, when these jacks are at the control station; that is to say, the highest end 51 of each group is placed at the level of the path through its control station of those control butts 30 which are farthest removed from the lower ends of the jacks, the next highest end 51 of the group is placed at the level of the path through its control station of those control butts 30 which are one step nearer the lower ends of the jacks, and so on, the lowest end 51 of the group being at the level of the path of those control butts 30 which are nearest the lower ends of the jacks (Fig. 8). Also, the sliding of each coupler moves it between a position where its end 51 is so close to the cylinder 1 that it will be struck by a butt 30 allocated to it as that butt passes through its control station, and a position sufficiently remote from the cylinder to permit its butts 30 to pass it without striking (Figs. 2 and 4). Intervals are provided during which no coupler of a given group is acting on a jack, and in these intervals the couplers of that group are newly positioned as the pattern may call for. Such intervals may be provided, for example, by providing in each jack lot a few adjacent jacks having no control butts 30, but in order to control every stitch I preferably so dispose the coupler ends 51 of each group in its control space that each group acts on the jacks and needles, to make its control manifest, at a rate that is higher (more per unit of time) than the rate at which the raising cam 16 of the same feed can act on jacks and needles; that is to say, the assembly of the coupler ends 51 of each group is such that, although one of the coupler ends 51 can act on the first jack of each jack lot (e. g. act on jack 15^a) before the last jack of the same jack lot (e. g. jack 15^b) arrives at the position of the coupler end provided to act on the latter, all the control butts 30 of a jack lot can be engaged by a coupler group in less time than the jack lot can pass over the top of one of the raising cams 16. This difference in rates produces intervals in which the couplers must rest from acting on the rotating bank, and during such intervals the couplers of the respective group can be reset in accordance with a new pattern call. The disposition to obtain this higher rate of coupler control can be obtained by, generally speaking, so placing the coupler ends 51 that as the bank rotates the control butt 30 of

the last jack of each jack lot (e. g., jack 15^b) leaves the position of the coupler provided to engage it a little time before the first jack of the next lot (e. g., jack 15^c) arrives opposite the coupler that is provided to engage such first jack. For example, if the control butts 30 of the jacks are arranged in substantially diagonal lines as before described, then each group of coupler ends 51 can be arranged more or less diagonally also, 5 inclined in the same general direction, but at a steeper angle (and also all within the control space, e. g. between the two ends of the associated cam extension 18). A strictly diagonal arrangement of the coupler ends is not necessary 10 however (when the disposition of the control butts 30 is diagonal), but any arrangement that sufficiently approximates the diagonal to secure the desired interval may be used, and a convenient arrangement is in two vertical assemblies of 15 adjacent ends (Figs. 5 and 8), the assembly containing the coupler which acts on the first jack of each lot (here the top coupler) being placed at that end of the control space which is adjacent the raising cam 16 of the same feed 20 and the assembly which contains the coupler which acts on the last jack of the jack lot (here the bottom coupler) being placed near the opposite end of the control space (Fig. 8). As an example of the intervals provided by such an arrangement of the coupler ends 51 of each group, it will be observed at the left side of Fig. 8 that all the jacks 15 of the jack lot 15^a—15^b excepting the last jack 15^b, have departed from their respective coupler ends 51 of the lefthand group 25 and all the jacks of this lot have been subjected to the control of this coupler group; however, the first jack 15^c of the next jack lot 15^c—15^d is still seven needles away from engagement with the coupler allocated to it in this lefthand coupler-group. In other words, the left-hand coupler group of this Fig. 8 having completed its action in controlling the jacks (and needles) of lot 15^a—15^b, must wait an interval corresponding to the time taken for seven needles to pass a given 30 point before beginning its control action on the succeeding jack lot 15^c—15^d. An interval may be lengthened or shortened by lengthening or shortening the length of the control space (e. g., lengthening or shortening the space between an initial-raising or placing cam 28 and the raising cam 16 which follows it) and correspondingly increasing or decreasing the separation between the two assemblies of the ends 51 of the coupler group acting at that space. Generally speaking, the minimum length of a control space is determined by the length of time required to bring each new pattern call to a rotating bank as will become clear. 35 As before mentioned, the sliding of the couplers 49, individually, places their ends 51 in their two possible positions (Fig. 4). The inward movements of the couplers of any group to the jack-engaging positions, are caused by the adjacent feeler ram 43; as this ram moves toward the needle cylinder it engages the butts 42 of such of the feelers 38 as are held in their upper positions by imperforate portions of the associated pattern 36 and thereby pushes those feelers inwardly, and those feelers push ahead 40 of them the couplers 49 allocated to them respectively. The couplers are returned to their outer or non-active positions by an upstanding butt 54 on each coupler and a ram 55 sliding horizontally in cross-heads in the side wall 6 of 45 each pattern section (Figs. 3 and 4). In the

present instance the coupler ends 51 of each coupler group are supported individually, immediately outside the needle cylinder, by a slotted frame or frames 56 (Figs. 3, 4 and 5). The couplers 49 are bent as necessary (Figs. 3, 4 and 5) to permit the outer ends of each group to lie in a row at a pattern section (Fig. 4) and the inner ends 51 of each group to lie in these frames 56 and the two assemblies described (Figs. 4, 5 and 8). Preferably I lock the coupler ends 51 in their inner or butt-engaging positions to assure these ends remaining in the inner positions against the thrust of the control butts 30 of the jacks on them, as by providing each end 51 with a slot 57 and providing a vertical bar 58 at each assembly to stand in the notches 57 of those coupler ends 51 which are in their inner or butt-engaging positions. At its two ends each vertical bar 58 is mounted in brackets 59 which are keyed to a rotatable shaft 60 carried in fixed bearings supported by the machine base (Figs. 3 and 4); links 61 and a connecting member 62 (Figs. 3, 4 and 6) swing the two bars 58 of each coupler group into and out of locking positions. By inclining the walls of the slots 57 as shown in Fig. 4, the locking bars 58 act also to position the coupler ends 51 accurately at their butt-engaging positions.

The various parts so far described are to operate in particular time relations. As will appear, the form and nature of the devices and mechanisms by which the parts so far described are operated (like, in fact, a great many of the constructional details so far described) constitute no part of this invention whatsoever, and various kinds of devices and mechanisms can be used for the purpose. In order however that the timing may be made entirely clear, I shall describe the operating arrangements employed in the machine illustrated. A cross bar 66 at each pattern mechanism (Figs. 3 and 4) serves to lift those feelers 38 of the respective mechanism which find perforations in their pattern 36 and fall into a drum slot 35, in order that the drum and pattern 36 may be advanced to make new calls, and also returns outwardly such of the feelers as have been thrust inwardly by the feeler ram 43. The bar 66 extends through arcuate slots 67 in the side walls 6 of its pattern mechanism, and at each end is carried by an arm 68 hinged at 69 to the walls 6 of its pattern mechanism. One of these arms 68 has an angular extension carrying a pin 70 riding in an angled slot 71 in a cross-head 72 sliding in a guideway 73 fastened to the outer surface of one of the side plates 6 of its pattern mechanism. Also a ratchet wheel 75 is fastened to one end of the shaft 33 to which the associated pattern drum 34 is keyed and an arm 71 provided with a spring pressed pawl 78 to engage with the ratchet 75, is hung loosely on the same end of each shaft and connected to a lever 79 hinged to the side plate 6 and provided with a pin 81 riding in an angled slot 82 in the cross-head 72. The slots 71 and 82 are so proportioned and angled that each upward and return reciprocation of the cross-head 72 first swings its cross bar 66 outwardly, thus raising any of its associated feelers that have fallen on the previous call (raising them sufficiently to remove their fingers from the pattern perforations), and also returning outwardly the feelers 38 that have been moved inwardly by the ram 43, and then advances the pattern drum to bring another slot 35 and another call of the pattern below the

row of feeler fingers, and finally restores the cross bar 66 to its inactive position as shown, thus permitting the feeler fingers to feel the new call of the pattern. A spring pressed plunger 80 and coacting toothed wheel 76 attached to one end of the drum shaft 33 assures each groove 35 being brought directly underneath the row of feeler fingers 39 and the drum 34 being held stationary between such forward steps. Each cross-head 72 is reciprocated by an angled lever 83 hinged by a bracket to the stationary cover plate 7 of the machine base, a reciprocating slide 84 having a socket into which one end of lever 83 extends (Figs. 3 and 6) and which is held to the top of the cover plate 7 by housing 85, and a pin 86 projecting downwardly from the slide 84 through a slot 87 in the cover plate into a cam groove 88 provided in or on the horizontal extension 8 of the rotary needle cylinder 1 (Figs. 6, 7 and 8). This groove 88 is provided with offset or camming portions 88a to reciprocate the slide or slides 84 and thereby actuate the feeler cross bars 66 and advance the pattern drums 34 step by step as described; there are as many of these camming portions as there are lots of differentiated needles, one being allocated to the needle and jack lot 15a-15b, another to the needle and jack lot 15c-15d, and so on, and each is so located as to reciprocate the slide 84 of each controlled feed prior to the time the needle-and-jack lot it serves reaches the group of coupler ends 51 of the respective feed; when, for example, substantially all the stitch-forming elements of the bank are differentiated, each camming portion 88a may be so placed as to reciprocate a slide 84 to bring up a new pattern call for its needle-and-jack lot (e. g. 15c-15d) while the preceding needle-and-jack lot (e. g. 15a-15b) is passing over and thereby is being subjected to the control of the group of coupler ends which will act next on the jack-and-needle lot (15c-15d) served by that camming portion. Each connecting-member 62 of a pair of lock bars 58 is operated to swing those lock bars by a link 90, a lever 91 connected to the opposite end of the link and hinged at 92 to the upper surface of the cover plate 7, and a pin 93 extending from the opposite end of the lever through a slot 94 in the cover plate into a cam groove 95 in extension 8 from the rotating needle cylinder 1 (Figs. 6, 7 and 8); cam offsets 95a in this groove (one offset for each lot of differentiated needles) act on the pin or pins 93 to swing the levers 91 and thereby the vertical lock bars 58. Each cam offset 95a is so located as to swing to their unlocking positions the pair of bars 58 associated with the group of coupler ends 51 which the needle-and-jack lot allocated to the respective cam offset is approaching, after the preceding needle-and-jack lot leaves that group of couplers, and return those lock bars to their locking positions just before the respective needle-and-jack lot reaches that group of couplers; between these two times the cam offset 95a holds those lock bars in unlocked positions. Each coupler ram 55 is operated by links 96 at its two ends, two arms 97 connected to the two links and keyed to a shaft 98 carried in the two side walls 6 of its pattern mechanism, and an arm 99 (between the side plates) which also is keyed to the shaft 98 and extends through a slot 100 in the cover plate 7 into a cam groove 101 in the annular extension 8 from the needle cylinder 1 (Figs. 3, 6, 7 and 8); cam offsets 101a in this

groove (one for each lot of differentiated needles) swing the respective arms 99 and 97 and thereby reciprocate their ram 55. Each offset 101^a is so located as to move a (and each) ram 55 outwardly to return the couplers 49 to their outer or non-active positions, and immediately return the ram to its inner position (Figs. 3 and 4), immediately after the lock bars 58 of the coupler group with which it is associated has swung to unlocking position. Each feeler ram 43 is operated by links 103 coupled to swinging arms 104, one at the outside of each side plate 6 of its pattern section, and which are keyed to a cross shaft 105 mounted in the side plates 6, and an arm 106 (between the side plates) which extends through a slot 107 in the cover plate 7 and thence into a cam groove 108 in the annular extension 8 from the needle cylinder (Figs. 3, 4, 6, 7 and 8); cam offsets 108^a in this groove (one for each lot of differentiated needles) swing the arm 106 (and each of them) to move the respective feeler ram 43 inwardly (toward the needle cylinder) as the associated coupler ram 55 is moved inwardly, or immediately thereafter, and restore the feeler ram 43 to its outer position (Figs. 3 and 4) before its associated feelers 38 are next raised by the action of the cam groove 88. The ram 43 in moving inwardly, passes above those of its feelers 38 that have found pattern perforations, but pushes ahead of it the remaining feelers and their respectively associated couplers, thereby transmitting the call of the pattern section 36 to the couplers 49 and positioning the latter for action on the rotating bank as directed by the pattern, as before described.

Primarily the operation at each pattern mechanism and group of couplers is, therefore, as follows, referring to Fig. 8: In the position of the parts as shown in that figure, the pattern element 36 serving the coupler ends 51 of the group shown at the left of Fig. 8 has been advanced to make a new call on the feelers 38 of those couplers, but the new call has not yet been transmitted to those couplers; i. e., those coupler ends are still in the positions given them in response to the preceding call of that pattern. The needle-and-jack cylinder rotating continuously in the direction of the arrow 11 of that figure, all the jacks of the lot 15^a—15^b have been acted on by this group of coupler ends 51 at the left of Fig. 8; accordingly the preceding pattern call has been transmitted to all the jacks and needles of the lot 15^a—15^b, the engagement of butts 30 of those jacks allocated to coupler ends of this group that have been placed close to the cylinder by the preceding pattern call has thrust those jacks to the back of their slots, thereby placing the butts 19 of such jacks back of the needle-raising cam 16 at the left of Fig. 8, and all the other jacks have been allowed to remain in their outer positions with their butts 19 in position to pass over that cam 16. Obviously all of the jacks of the lot might have been thus thrust to the back of their slots if the pattern had so called, or all might have been left in their outer positions. The rotation of the cylinder causes the butts 19 of those jacks that are left in their outer positions, to pass over cam 16 at the left of the figure and thereby raise their needles to take yarn (with or without the aid of the cam 20 as before explained) as will be apparent; the remainder pass back of the same cam 16 at their lower position and hence fail to raise their respective

needles 2 at this feed; incidentally, in the position of the parts shown, some of the lot 15^a—15^b have already passed over or by this cam 16. The preceding pattern call for this feed having thus been transmitted to all the stitch-forming elements of the jack lot 15^a—15^b, and the adjacent jack lot 15^c—15^d not yet having reached the same group of coupler ends 51 (or to the location of these coupler ends with respect to the control butts 30), those couplers 49 of this group that were projected in accordance with the preceding pattern call, are now (with their ends 51) returned to their outer positions (e. g., by reciprocation of the ram 55), and immediately all the couplers 49 of the group (and thereby their ends 51) are repositioned in accordance with the new pattern call (e. g., by the reciprocation of the ram 43 of the respective pattern mechanism, this acting on the couplers through those feelers 38 that have found no perforations in the pattern below their fingers). If locking mechanisms for the couplers are provided, of course they are unlocked just before any of these couplers are returned to their outer positions (as by swinging locking bars 58 to their unlocked positions), and they are locked again immediately after the couplers are repositioned in accordance with the new pattern call (as by returning the locking bars 58 of the group to locking positions). This repositioning of the coupler ends 51 of the group at the left of Fig. 8 in accordance with the new pattern call, has taken place before the first jack of the jack lot 15^c—15^d reaches the place of its respective coupler end of this group. Accordingly as the continued rotation of the needle and jack cylinder passes the jack lot 15^c—15^d over this group of coupler ends, the jacks 15 of this lot 15^c—15^d are acted on in accordance with the new pattern call, some probably (as directed by the new pattern call) being thrust to the backs of these slots and others being allowed to remain in their outer positions where they will pass over the raising cam 16 at the left of Fig. 8 and raise their needles (or cause them to be raised) to take yarn at this feed. Further, while the new pattern call is thus being transmitted to the lot 15^c—15^d, the feelers 38 that fell when the new call was made by the pattern element 36, are raised to withdraw their fingers 39 from their perforations in the pattern (e. g. by the swinging of their cross bar 66), the pattern or pattern element 36 is advanced a step to bring the next pattern call below the row of feeler fingers 39, and the row of feeler fingers 39 again is permitted to feel the pattern and accordingly their feelers 38 positioned in accordance with this next call. This completes the cycle of operations; when the lot 15^c—15^d leaves this group of coupler ends 51, these coupler ends are repositioned again (responsive to such next pattern call, and for the needle lot beginning with 15^e which follows 15^c—15^d) as described above. As jacks and needles pass a cam 16, they are lowered by the cams 22 and 21, and the lower ends of the jacks are thrust out, for example, by the inclines 25 as described. It will be observed of course that a new pattern call and a corresponding repositioning of this group of feeler ends 51 may be made (and is made in the machine illustrated) for each pass of a differentiated lot of the rotary cylinder over this group of coupler ends, and also that each pattern mechanism or pattern mechanism section and coupler group of the machine may act sim-

ilarly (and does act similarly in the machine here illustrated), and accordingly the operation of every differentiated needle may be controlled at every feed.

From this it will be observed that, more essentially, my invention consists of the following: A group of coupler ends, so called, the exact nature of which is unimportant, is provided for each feed of the machine whereat the action of a bank of stitch-forming elements is to be controlled; the (and each) group is mounted in a fixed position as it were, that is to say, it does not rotate with the bank of controlled stitch-forming elements but acts on the elements of the bank as these respectively pass the position of the group. The stitch-forming elements are differentiated among themselves in lots in such a way that each differentiated element (or differentiated set of, say, a few adjacent elements) is subjected to the control of, say, one particular coupler end of the group (and each of the groups); preferably the differentiation of each lot is like the differentiation of every other lot, this rendering the preparation of the controlling patterns more convenient. A pattern mechanism is provided, the calls of the pattern of which couplers (with their ends) transmit to the stitch-forming elements; the arrangement accordingly is such that a pattern mechanism of the kind which is adapted to be directed by a pattern of paper or other sheet-like material, and one having its pattern-calls (e. g. and preferably perforations) arranged in rows transversely, can be used, and preferably one of the various possible forms of pattern mechanisms of this kind is used; preferably there is such a pattern mechanism for each feed whereat the action is to be controlled, and each group of coupler ends is related to and therefore subject to the call of one pattern mechanism or pattern mechanism section serving the respective group alone. Suitable means or mechanism (the nature of which is unimportant) is provided to advance the (each) pattern of the pattern mechanism to make a new call, and also to actuate the couplers of the (each) group responsive to a new pattern call, for, say, each passage of each differentiated lot of stitch-forming elements across the respective coupler group. While the coupler ends, so-called, are so disposed that, for any row of pattern calls, the first of a (each) lot of differentiated elements can be acted on by a coupler end before the last element of the same lot is acted on by a coupler end of the same group, intervals are provided during which no coupler of a group is capable of acting, and during these intervals the couplers of the respective group are actuated to transmit the successive calls of the pattern to the region of the stitch-forming element bank, that is to say, the group is prepared to act on an oncoming stitch-forming element lot as directed by a new pattern call; preferably these intervals are provided by so locating the couplers that the group transmits each pattern call to the stitch-forming element bank at a rate higher than the rate at which the respective feed can actuate stitch-forming elements in their stitching movements. Preferably also the pattern feelers are so disposed that they can be withdrawn from the pattern and the (each) pattern is advanced, while the related couplers are acting on the stitch-forming element bank, i. e. are transmitting the prior call of the pattern to the bank.

As indicated, and as will be apparent to those

skilled in this art, the various parts and mechanisms of my invention as specifically shown in the accompanying drawings are subject to considerable modification in form and structure; for example, various other forms of pattern mechanisms, coupler bodies and coupler ends, and mechanisms for operating the parts, and various arrangements for differentiating stitch-forming elements for more or less individual operation and control by devices outside their bank, are already known and others are readily devisable, and may be substituted for the particular forms of these devices employed in the machine illustrated. It will be understood also that, generally speaking, there may be as many lots of differentiated stitch-forming elements as desired, and only so many of a bank of stitch-forming elements may be differentiated for control by the pattern and couplers as may be sufficient or deemed necessary in any instance, the remainder being allowed to operate in the same manner at say every pass of every feed, and also that the omission of differentiation from some of the elements may lengthen or even provide the interval for coupler operation which I have provided by the peculiar illustrated arrangement of the coupler ends 51 with respect to the control butts 30. Generally speaking too, there may be as many feeds on the machine as the diameter of the machine permits, or less than this, and also as before indicated, the reference herein to the allocation of a feeler finger to each coupler includes allocation of a feeler finger to individual sets of a few adjacent couplers. In general, my invention is not limited to the details that are necessarily referred to above and shown in the accompanying drawings, except as appears hereafter in the claims.

I claim:

40. 1. In a knitting machine, a circular bank of stitch-forming elements, a pattern mechanism, a lot of members rotatable around the axis of said bank to control the action of said stitch-forming elements, and a group of coupler members to control the action of said lot of controlling members, said lot of members rotating with respect to said pattern mechanism and group of coupler members and said coupler members acting on the members of said lot to transmit the pattern calls thereto as the rotation of the lot carries the lot past the group, the coupler members and the members of said lot being so located with respect to each other that the first member of said lot arrives at the position of the coupler member serving it before the last member of said lot arrives at the position of the coupler member serving such last lot member and the coupler members can act on the members of the lot at a rate higher than the rate at which said stitch-forming elements act in forming stitches.
45. 2. In a knitting machine, a bank of members including stitch-forming elements, pattern mechanism including a pattern advanceable to make new calls, a plurality of feeds each of which include means to actuate said stitch-forming elements in the formation of stitches and a group of coupler members to control the actuation of the stitch-forming elements by said stitch-forming-element-actuating means in accordance with the call of said pattern, said bank rotating with respect to said stitch-forming-element-actuating means, pattern mechanism and groups of coupler members so that said actuating means and coupler members act on members of the bank as the rotation of the bank carries the members of the
50. 3. In a knitting machine, a bank of members including stitch-forming elements, pattern mechanism including a pattern advanceable to make new calls, a plurality of feeds each of which include means to actuate said stitch-forming elements in the formation of stitches and a group of coupler members to control the actuation of the stitch-forming elements by said stitch-forming-element-actuating means in accordance with the call of said pattern, said bank rotating with respect to said stitch-forming-element-actuating means, pattern mechanism and groups of coupler members so that said actuating means and coupler members act on members of the bank as the rotation of the bank carries the members of the
55. 4. In a knitting machine, a bank of members including stitch-forming elements, pattern mechanism including a pattern advanceable to make new calls, a plurality of feeds each of which include means to actuate said stitch-forming elements in the formation of stitches and a group of coupler members to control the actuation of the stitch-forming elements by said stitch-forming-element-actuating means in accordance with the call of said pattern, said bank rotating with respect to said stitch-forming-element-actuating means, pattern mechanism and groups of coupler members so that said actuating means and coupler members act on members of the bank as the rotation of the bank carries the members of the
60. 5. In a knitting machine, a bank of members including stitch-forming elements, pattern mechanism including a pattern advanceable to make new calls, a plurality of feeds each of which include means to actuate said stitch-forming elements in the formation of stitches and a group of coupler members to control the actuation of the stitch-forming elements by said stitch-forming-element-actuating means in accordance with the call of said pattern, said bank rotating with respect to said stitch-forming-element-actuating means, pattern mechanism and groups of coupler members so that said actuating means and coupler members act on members of the bank as the rotation of the bank carries the members of the
65. 6. In a knitting machine, a bank of members including stitch-forming elements, pattern mechanism including a pattern advanceable to make new calls, a plurality of feeds each of which include means to actuate said stitch-forming elements in the formation of stitches and a group of coupler members to control the actuation of the stitch-forming elements by said stitch-forming-element-actuating means in accordance with the call of said pattern, said bank rotating with respect to said stitch-forming-element-actuating means, pattern mechanism and groups of coupler members so that said actuating means and coupler members act on members of the bank as the rotation of the bank carries the members of the
70. 7. In a knitting machine, a bank of members including stitch-forming elements, pattern mechanism including a pattern advanceable to make new calls, a plurality of feeds each of which include means to actuate said stitch-forming elements in the formation of stitches and a group of coupler members to control the actuation of the stitch-forming elements by said stitch-forming-element-actuating means in accordance with the call of said pattern, said bank rotating with respect to said stitch-forming-element-actuating means, pattern mechanism and groups of coupler members so that said actuating means and coupler members act on members of the bank as the rotation of the bank carries the members of the
75. 8. In a knitting machine, a bank of members including stitch-forming elements, pattern mechanism including a pattern advanceable to make new calls, a plurality of feeds each of which include means to actuate said stitch-forming elements in the formation of stitches and a group of coupler members to control the actuation of the stitch-forming elements by said stitch-forming-element-actuating means in accordance with the call of said pattern, said bank rotating with respect to said stitch-forming-element-actuating means, pattern mechanism and groups of coupler members so that said actuating means and coupler members act on members of the bank as the rotation of the bank carries the members of the

bank past said means and coupler members, substantially successive members of the rotary bank being differentiable among themselves by lots, the number of differentiable members in each lot substantially corresponding to the number of coupler members in each group of the latter and the members of each lot being differentiable among themselves for substantially individual control by substantially individual coupler members of each coupler member group, and the coupler members being so located with respect to the differentiable members that the first of a lot of differentiable members arrives at the position of the coupler member allocated to it before the last member of the same lot arrives at the position of the coupler member allocated to such last member, and means to actuate coupler members of each feed, responsive to new pattern calls, substantially as many times in each rotation of said bank as there are lots of differentiable members in the rotary bank.

3. In a knitting machine, a bank of members including stitch-forming elements, means adapted to actuate said stitch-forming elements substantially successively in the formation of stitches, a pattern mechanism including a pattern element having pattern-calling agencies and movable to make new calls, a group of coupler members to control the actuation of stitch-forming elements by said means in accordance with the calls of said pattern element, said bank rotating with respect to said actuating means, pattern mechanism and group of coupler members and the coupler members acting on members of the rotary bank to transmit the pattern calls thereto as the rotation of the bank carries the members of the bank past the group, a lot of substantially successive members of the bank being differentiated among themselves for substantially individual control by substantially individual coupler members of the group, another lot of substantially successive members of the bank also being differentiated among themselves for substantially individual control by substantially individual coupler members of the same group, and said coupler members being so located with respect to the differentiated members of the rotating bank that the first member of a lot of differentiated members arrives at the position of the coupler members serving it before the last differentiated member of the same lot arrives at the position of the coupler member serving such last differentiated member and the said coupler members can act on the differentiated members at a rate higher than the rate at which said stitch-forming-element-actuating means can actuate said stitch-forming elements whereby intervals are provided during which none of said coupler members are active on differentiated members of the rotating bank, and means to actuate coupler members of the group, responsive to new pattern calls, during such intervals.

4. The subject matter of claim 3, characterized by the fact that said pattern element, in advancing to make new calls, brings to active position the new calls for a plurality of said coupler members substantially simultaneously.

5. The subject matter of claim 3, a plurality of feeler fingers being provided to coact with the pattern element, each of the feeler fingers being allocated to substantially a single coupler member and said fingers being arranged in a row to coact with the pattern element substantially simultaneously.

6. The subject matter of claim 3, characterized

by the fact that the members of the first-mentioned lot of members of the rotating bank, are differentiated from each other successively in substantially the same manner as the members of 5 the second mentioned lot are differentiated from each other successively, whereby corresponding members of both lots are controllable by, respectively, the same coupler members.

7. The subject matter of claim 3, the pattern-calling agencies of the pattern element being perforations, characterized by the fact that a plurality of fingers, allocated to the coupler members, are provided to pass through the perforations of the pattern element, the fingers being withdrawn from the perforations of a call before 15 the group of coupler members completes the transmission of the respective call to members of the bank, and said pattern-advancing means advances the pattern element to make a new call while the group of coupler members is transmitting the prior call to such members.

8. The subject matter of claim 3, the pattern-calling agencies of the pattern element being perforations, characterized by the fact that a plurality of fingers, allocated to the coupler members, are provided to pass through the pattern perforations of the pattern element, means are provided to withdraw said fingers from the perforations while the group of coupler members is 25 acting on members of the rotating bank, and said pattern-advancing means advances the pattern element to make new calls while the group of coupler members is acting on members of the rotating bank.

9. The subject matter of claim 3, characterized by the fact that said coupler members are arranged in a plurality of assemblies, each assembly being more or less parallel to the differentiated members of the bank and the assembly containing the coupler member which acts on the first differentiated member of each lot being placed closer to said stitch-forming-element-actuating means than the assembly which contains the coupler member which acts on the last differentiated member of each lot.

10. In a knitting machine, a bank of members including stitch-forming elements, a cam to actuate said stitch forming elements to form stitches, a pattern mechanism including a pattern element perforated in accordance with the stitch-forming-element-actuation desired at said cam, the perforations thereof being arranged substantially in rows extending substantially transversely of the pattern element, a group of 35 coupler members responsive to the calls of perforations of the pattern element and individually movable to and from positions whereat the coupler members are engageable by the butts on members of the rotary bank hereafter mentioned, said bank rotating with respect to said cam, pattern mechanism and coupler members and the ends of said coupler members engageable by said butts being assembled together in advance of said cam, a lot of substantially successive members of the rotary bank being provided with butts differently located on the said members for engagement with substantially individual coupler members, another lot of substantially successive members of the rotary bank also being provided with butts differently located on the latter members 40 for engagement with substantially individual coupler members of the same group, said members of both lots being displaceable by the engagement of their butts with the coupler members to control the actuation of the respectively 45

corresponding stitch-forming elements by said cam, and said coupler members being so located with respect to the members of such lots that the butt of the first member of a lot is engageable by the coupler member before the butt of the last member of the same lot is engageable by a coupler member and the said coupler members can engage the butts of said members of the bank at a rate higher than the rate at which said cam can actuate the stitch-forming elements whereby intervals are provided during which none of said coupler members are engageable with said butts, and means to advance said pattern element to make a new call, and also to move coupler members of the group to establish placement of the coupler members with respect to said butts responsive to such new call, for each passage of each of said lots of members across the group of coupler members, said coupler-moving means moving at least some of said coupler members responsive to the pattern calls during such intervals.

11. In a knitting machine, a rotary bank of members including stitch-forming elements, a stationary cam to actuate said stitch-forming elements in the formation of stitches, a pattern mechanism including a pattern element perforated in accordance with the stitch-forming element-actuation desired at said cam, the perforations thereof being arranged substantially in rows extending substantially transversely of the pattern element, a stationarily-placed group of coupler members individually movable to and from positions whereat the coupler members are engageable by the butts on members of the rotary bank hereafter mentioned and the ends of said coupler members engageable by the said butts being assembled together in advance of said cam, a lot of substantially successive members of the rotary bank being provided with butts differently located on the said members for engagement with substantially individual coupler members, another lot of substantially successive mem-

bers of the rotary bank also being provided with butts differently located on the latter members for engagement with substantially individual coupler members of the same group, said members of both lots being displaceable by the engagement of their butts with the coupler members to control the actuation of the respectively-corresponding stitch-forming elements by said stationary cam, and said coupler members being so located with respect to the members of such lots that such butt of the first member of a lot of the latter members arrive at the position of the coupler member engageable with it before the butt of the last member of the same lot arrives at the position of the coupler member with which the last-mentioned butt is engageable and the said coupler members can engage the butts of said members of the rotating bank at a rate higher than the rate at which said cam can actuate said stitch-forming elements whereby intervals are provided during which none of said coupler members are engageable by said butts, a group of feeler fingers, allocated to the coupler members, to pass into the perforations of the pattern element and thus differentiate the coupler members among themselves, means to move the coupler members to establish the placement of the coupler members with respect to said butts, said coupler-member-moving means moving coupler members differentiated from the others by some of said fingers entering perforations in the pattern element and acting on each pass of each of said lots of members across the group of coupler members and moving said coupler members during said intervals, and means to withdraw feeler fingers from said perforations and advance the pattern element to make new calls, the last named means acting on each pass of each of said lots of members across the group of coupler members and acting while the coupler members are acting on butts of the members of the rotating bank.

J. STANLEY PRESTON.
